SEWING-MACHINE.

1,311,114.

Specification of Letters Patent. Patented July 22, 1919.

Application filed December 20, 1916, Serial No. 137,946. Renewed November 4, 1918. Serial No. 261,149.

To all whom it may concern:

Be it known that we, OLIVER L. DOSCH and MARTIN HEMLEB, citizens of the United States, residing at Elizabeth, in the county 5 of Union and State of New Jersey, have invented certain new and useful Improvements in Sewing-Machines, of which the following is a specification, reference being had thereto in the accompanying drawings.

10 This invention relates to an improvement in sewing machines, and more particularly to machines so constructed that a driving motor may be embodied as one of the units of its organism.

15 The invention has for one of its objects to provide a sewing machine with a motor extending into its frame to insure compactness and protection against disarrangement of its parts. It has for other objects to pro- 20 vide such a motor capable of easy removal for access to its parts or for repair without dismantling or rendering the machine inoperative; also to provide means whereby the machine may be operated by hand, foot 25 or motor drive; and also to provide for the coupling and uncoupling of the various driving means and the operative parts of the sewing mechanism to permit of the use 30 of the driving means independently of the stitch-forming devices for certain operations, such as the winding of bobbins, the sharpening of needles &c.

In its preferred embodiment, the sewing machine is constructed with the usual form 35 of frame comprising a bed-plate from which rises a hollow standard sustaining the over- hanging tubular frame member in which is journaled the main-shaft having usual or suitable connections with a reciprocating 40 needle. Coöoperating with the needle is a suitable loop-taking element below the bed-plate which has operative connections beneath the latter and through the hollow standard with the main-shaft.

45 The main-shaft is preferably formed in forward and rearward sections, the former which drives the needle being journaled in spaced bearings within the tubular arm of the frame and the latter section being 50 journaled within a bearing at the upper end of the standard and spaced from the adjacent bearing of the tubular arm; provision being made for coupling and uncoupling these main-shaft sections.

The rearward main-shaft section has se- 55 cured thereon externally of the machine frame a driving pulley to receive a belt from the band-wheel of a treadle mechanism, and adjacent the same a connection with a crank- operated hand-driving device with means 60 for throwing it into and out of driving relation therewith.

The machine frame is preferably formed at the junction of the standard and the over- hanging arm with an aperture or opening 65 surrounded by a seat to which is fitted the cylindrical rim of an electric motor-frame which is provided with suitable means for removably securing it in position. The driv- 70 ing connection between the motor-shaft and the rearward main-shaft section of the ma- chine is of such a nature that operative re- 75 lation between said shafts is established by the mere act of insertion of the motor-unit in the aperture or opening in the sewing 75 machine frame. The motor comprises pref- erably a stationary field or stator sur- 80 rounding a rotary armature or rotor which is mounted upon a shaft carrying an angular gear meshing with a similar gear loosely 85 mounted upon the rearward section of the main-shaft. A one-way-acting clutch is preferably provided between the loosely mounted angular gear and its sustaining 90 shaft section whereby its rotation in one di- 90 rection causes the rotation of the shaft while the rotation of the shaft in the same direc- 95 tion by other driving means permits the gear and the connected motor armature to remain idle.

It is desirable that the motor be applied to the bracket-arm and intermediate the stitch-forming mechanism at one end and the balance-wheel at the opposite end there- 95 of, and that it be housed as far as possible within the bracket-arm, not only to insure compactness and attractiveness of appear- 100 ance of the machine as a whole but to permit of its being applied to a well-known form of drop-head treadle-stand in which the capacity of the receptacle for the sew- 105 ing machine frame is necessarily limited. It is also desirable that the sewing machine structure and the motor may be of such character that the sewing machine may be initially equipped with the motor or may be furnished with a motor at any time subse- 105 quently that such equipment may be de-

sired without reconstruction or special fitting. To this end, it is one of the characteristic features of the present improvement that the motor is so constructed and arranged that its armature- or power-shaft is disposed transversely of the main-shaft or, at any rate, is directed to one side of the stitch-forming mechanism as distinguished from constructions in which the motor-shaft is arranged in alinement with the main-shaft of the sewing machine and is therefore directed toward the stitch-forming mechanism.

Another important characteristic of the invention is the provision of a readily detachable motor unit applied to the goose-neck of the sewing machine frame and received, at least partially, within a recess in said frame so as to secure as far as possible the compactness and attractive appearance of a built in construction, without sacrifice of the feature of ready detachability of the motor.

In the accompanying drawings, Figure 1 is a front side elevation, partly in section, representing a sewing machine embodying the present invention, and Fig. 2 a rear end elevation of the same, partly in transverse section. Fig. 3 is a perspective view, partly in section, of the motor detached from the machine. Fig. 4 is a perspective view representing the rearward section and a part of the forward section of the main-shaft of the machine, with one of the angular gears by which it is connected with the motor armature shaft, and Fig. 5 a similar view of the coupling element for the main-shaft sections. Fig. 6 is a partial sectional view of the frame, showing a substantially flat cover-plate employed when the motor is not applied to the machine. Fig. 7 is a perspective view of the housing for the hand-actuated driving gear.

As represented in the drawings, the machine is constructed with a frame of well-known form comprising the bed-plate 1 from which rises the goose-neck comprising the hollow bracket-arm standard 2 and tubular arm 3 in the head 4 of which is journaled the reciprocating needle-bar 5 carrying the needle 6. The tubular arm 3 is provided with the longitudinally spaced bearing bushings 7 and 8 in which is journaled the forward or needle-actuating shaft-section 9 of the two-part main-shaft 9, 10, the latter section of which is tubular, being disposed in alinement with the former and journaled in turn within a suitable bearing boss 11 disposed at the upper end of the standard 2 and spaced from the bearing bushing 8.

The needle-bar derives its operative movements from a crank-and-pitman connection with the forward end of the shaft section 9 in a manner well-known. The needle 6 co-

operates in the production of stitches with a rotary loop-taker 12 mounted beneath the bed-plate upon the upper end of the vertical loop-taker shaft 13 which carries upon its lower end the beveled pinion 14 meshing with a larger bevel gear 15 upon the forward end of the rotary shaft 16 mounted in bearings 17 depending from the bed-plate. The rearward portion of the shaft 16 is connected by means of the intermeshing bevel gears 18 and 19 with the intermediate shaft 20 extending upwardly through the standard 2 and connected by means of the bevel gears 21 and 22 with the main-shaft section 9. The gear-connected shafts 9, 20, 16 and 13, thus constitute actuating mechanism interconnecting the needle 6 and loop-taker 12 and insuring their co-operation in properly timed relation.

The rearward or driving section 10 of the main-shaft is loosely surrounded by a bushing 23 affording one member of an anti-friction bearing and having in its opposite ends annular raceways to receive the series of anti-friction balls 24. One series of these balls is confined in its respective raceway by means of a collar 25 affording a complementary raceway and the other series is confined within its respective raceway by a collar 26 secured upon said shaft by means of the set-screw 27 and grooved in its inner end to afford a complementary raceway to the opposed raceway of the bushing.

The adjacent ends of the shaft sections 9 and 10 are shown formed with transverse slots 28 and 29 respectively, to receive the coupling key-plate 30 secured by means of the cross-pin 31 in a transverse slot at the end of the coupling rod 32 passing through the bore of the shaft section 10 and carrying upon its opposite end the button 33. The shaft-section 9 may, of course, be regarded as an actuating shaft for the stitch-forming mechanism, and the tubular shaft-section 10 may be regarded as a second shaft adapted to be operatively connected with and disconnected from the actuating shaft at the will of the operator.

The rearward end of the tubular shaft section 10 has secured thereon exterior to the machine frame by means of the set-screw 34 the hub 35 of a balance-wheel 36 formed with the integral grooved belt-wheel 37 which is shown embraced by the driving belt 38 from a source of power, such as the band-wheel of a treadle device.

The fixed collar 26 forms the hub of a gear 26' having peripheral teeth adapted to mesh with those of a larger driving gear 39 whose hub 40 is journaled upon the shouldered stud-screw 41 tapped into the standard 2. The outer portion of the hub 40 is formed with a cavity adapted to receive the head of the stud-screw 41 and threaded in its outer end to fit the correspondingly 130

threaded outer portion of a screw-plug 42 upon the hub of a crank-arm 43 carrying at its outer end the handle 44.

When the hand driving-attachment thus formed is not in use, the crank 43 and its screw-plug 42 are removed and the driving gear 39 is pressed inwardly out of mesh with the gear 26', the peripheral teeth of the gear 39 resting against the detaining spring 45 whose offset operative free end enters a peripheral slot 46 in the rim 47 of the segmental gear housing 48 which is formed with an aperture 49 to receive the shouldered stud-screw 41 by which it is secured to the standard 2; the spring 45 having its opposite end secured by the screw 50 to the periphery of the rim 47. To adjust the hand-driving device for operation, the plug 42 is screwed into the socket of the hub 40, and its engagement with the head of the stud-screw 41 causes the driving gear 39 to be drawn outwardly into mesh with the gear 26', in which position of the parts the hub of the crank 43 becomes seated upon the end of the hub 40, so that the continued turning of the crank causes the driving of the shaft section 10 through the intermeshing gears 26' and 39.

The goose-neck of the machine frame is formed at the junction of the standard 2 and the tubular arm 3 with an aperture or opening 51 whose inner wall forms an annular seat to which is fitted the annular bearing rib 52 of the motor unit illustrated in Fig. 3. The motor-unit is constructed separately from the sewing machine frame and comprises a stator 53 which is represented as cup-shaped to afford in its outer or rearward side a cavity to receive the armature or rotor 54 and the surrounding series of coils 55 forming a part of the stator sustained by the laminated portion 56 of the stator-frame.

The stator-frame is provided upon its opposite face with the axially extending armature-shaft bearing-boss 57 formed intermediate its ends with the open-topped gear-cavity 58. The boss 57 is preferably provided with bushings 59 in which the armature-shaft is journaled. The hub 57 is suitably apertured to receive thimbles 60 containing the usual spring-pressed brushes 61 in the form of carbon pencils whose outer ends rest upon the adjacent face of the commutator 62 sustained at the inner end of the armature. The usual connection between the source of current supply and the brushes and the field coils, respectively, is made by means of the insulated wires 63 extending through the standard 2 and through the opening 64 in the bottom of the stator-frame.

The armature-shaft 65 has fixed thereon within the cavity 58 the angular or spiral gear 66 meshing with the larger angular gear 67 fitted loosely upon the main-shaft

section 10. The intermeshing spiral gears 66 and 67 thus constitute positively acting smooth and quiet running speed-reducing means which permits of the employment of a motor running normally at high speed 70 and therefore of minimum dimensions for the power to be developed; and this in turn facilitates the partial reception of the motor unit within the recessed goose-neck so as to afford compactness of the construction as 75 well as a high efficiency and the attractive appearance of a built-in construction.

The inner or hub portion of the gear 67 is formed with an eccentrically disposed clutch-cavity 68 merging at one end into its 80 bore and embracing within the same the clutch-roller 69 pressed normally toward the open end of the cavity by means of the spring 70 in a manner well known. The gear 67 is confined against the collar 25 of 85 its supporting shaft section and the clutch-roller 69 and its spring are retained within their cavity 68 by means of the collar 71 secured upon the shaft section 10 by means of the set-screw 72. The clutch connection between the stitch-forming mechanism and the 90 motor, afforded by the clutch-roller 69 and the walls of the clutch-cavity 68, acts automatically to disconnect the motor from the stitch-forming mechanism when the latter is 95 driven by hand- or foot-power.

When the sewing machine is in operative position upon its supporting table, the inner disk-shaped face of the motor-frame affords an effective barrier between the operative 100 parts of the sewing machine and the motor-armature and field to effectively exclude from the latter any oil and dirt that may be thrown off by the moving parts of the sewing machine within the hollow frame. To 105 afford proper lubrication for the gears 66 and 67, the cavity 58 is preferably partially filled with oil which in the operative position of the machine frame is confined therein to prevent undesirable spreading. To suitably confine the contained oil when the machine is turned sidewise for any purpose, as for adjustment of parts beneath the bed-plate, the inner face of the motor-frame is formed with a U-shaped rib 73 extending 110 from opposite sides of the cavity 58 so that the overflow of oil from the latter when the bearing boss 57 becomes backwardly inclined will be caught temporarily in the pocket thus formed, to be returned to the cavity 58 115 when the machine frame resumes normal operative position.

When the machine is applied to a drop-head cabinet of well-known form, below the top of which it is turned forwardly and downwardly when not in use, the oil from the gear-cavity 58 is received in two or more pockets 74 (Fig. 3) extending inwardly from such cavity, the oil thus caught being returned to the gear-cavity when the ma- 130

chine is next righted for a sewing operation.

At opposite sides of the gear 66, the bearing boss 57 is shown provided with the depending oil-cups 75 adapted to be screwed into threaded sockets 76 communicating with the bores of the bushings 59 in a manner well known. Needless to say, the motor-shaft 65, being disposed horizontally, may 10 be more efficiently lubricated than a vertically disposed motor-shaft.

As thus described, the motor constitutes a separate and distinct unit of the sewing machine which may be secured in place by a 15 single fastening screw 77 passing through the standard 2 and entering an aperture 78 in the end of the boss 57; and the motor may be removed without in any wise dismantling or disarranging the operative parts of the 20 sewing machine by merely removing the screw 77 or such other fastening means as may be provided.

As represented in Fig. 2, the motor is 25 preferably incased within a cap 79 having a rim fitted to the motor-aperture 51 of the machine frame; but in case it should be desired to furnish the machine unequipped with a motor drive, a flat cover-plate 80 (Fig. 6) may be employed in lieu of the 30 cylindrical cap 79.

The foregoing features are of prime importance inasmuch as the machine may be sold as a neat appearing treadle- or hand-operated machine with the cover-plate 80 applied to the aperture 51 and devoid of 35 unsightly external attachments, brackets or the like. Later on, if the user desires to avail himself of the motor-drive, a motor-unit may be purchased and readily fitted to 40 the recessed goose-neck or, in the embodiment shown, inserted in the aperture 51 in lieu of the cover-plate 80. The services of a skilled mechanic are not required to effect 45 the change from manual, *i. e.*, hand- or foot-power drive, to motor-drive. In the present embodiment of the invention the mere act of insertion of the motor in the opening or 50 aperture 51 establishes operative relation between the gears 66 and 67, thus connecting the motor to the machine. It will be noted 55 that the gear 67 is mounted on the shaft 10 which may be considered as a part of the manual drive inasmuch as power from the belt 38 or hand-crank 43 is transmitted to the stitch-forming mechanism through the shaft 10.

From the foregoing description it will be observed that the three different drives with 60 which the machine is equipped are all applied to what is herein termed the driving main-shaft section which is normally coupled to the driven main-shaft section by means of the key-plate 30 entering the slot 28 of the driven shaft section; and that any 65 one of these different drives may be operated

in the winding of bobbins or other operations unconnected with sewing by the mere retraction of the rod 32 to withdraw the key-plate 30 from the slot 28, thus manually releasing the stitch-forming mechanism from the motor and other drives. It is further to be noted that, while the treadle-actuated driving pulley 37 is fixed upon the driving section 10 of the main-shaft; the hand attachment is disengageable from such section 70 by lateral shift of the driving gear 39 and that the motor drive connection is rendered ineffective in the mere turning of the driving shaft section by either of the manual drives. It is thus evident that each of these drives 75 is operable independently of the others.

While the balance-wheel 36 is caused to rotate idly when the motor is in action, it will be observed that, although the motor may cause the machine to stop in a disadvantageous position of the needle the operator is free to manually turn the main-shaft by the use of the balance-wheel to adjust the needle to any desired position, either at its highest point for introduction or removal 85 of the work or at a lower position to enable the needle to serve as a pivot on which to revolve the work in turning a corner of a seam.

While the present improvement is shown 90 herein in what is deemed a preferable form, it is to be understood that the same is susceptible of very material modification in the construction and arrangement of its parts within the scope of the invention, and that the type of motor employed is not essential, although an electric motor is preferable because of the ease with which it may be controlled and supplied with the necessary power-medium for its operation. 95

Having thus set forth the nature of the invention, what we claim herein is:—

1. In a sewing machine, in combination, a frame formed with an aperture, stitch-forming mechanism comprising a reciprocating needle and complementary loop-taking means incorporated in said frame, operating mechanism interconnecting said needle and loop-taking means, a motor-unit comprising a stator detachably supported by said frame, 110 and a rotor journaled in said stator and including a power-shaft entering said aperture and operatively connected with said operating mechanism. 115

2. In a sewing machine, in combination, 120 a frame, stitch-forming devices and operating mechanism therefor including a shaft, a motor including a stator and a rotor, said stator being detachably sustained as a unit by said frame and said rotor having a power-shaft disposed transversely of said shaft, and an operative connection between said shafts. 125

3. A motor driven sewing machine having a frame formed with a recessed goose-neck, sewing mechanism incorporated in 130

- 5 said frame, a driving motor received at least partially within the recess of said goose-neck and detachable therefrom as a unit, and a driving connection between said motor and sewing mechanism.
- 10 4. In a sewing machine, in combination, a frame formed with an aperture, stitch-forming devices and operating mechanism therefor sustained by said frame, a motor-unit constructed independently of and sustained by said frame and having a power-shaft directed to one side of the stitch-forming mechanism and entering said aperture, and a driving connection between said power-shaft and said operating mechanism.
- 15 5. In a sewing machine, a frame having an opening therein, stitch-forming mechanism sustained by said frame, means for actuating said stitch-forming mechanism, and a readily removable actuating unit constructed separately from said frame and entering said opening, said unit having a driving connection operatively connectible with the stitch-forming mechanism by insertion in said opening.
- 20 6. In a sewing machine, in combination, a frame including a standard and an overhanging bracket-arm, stitch-forming devices and operating mechanism therefor incorporated in said frame and including a main-shaft, a motor detachably sustained by said frame independently of said operating mechanism and having a power-shaft disposed transversely of said standard and first-mentioned shaft, and an operative connection between said shafts.
- 25 7. In a sewing machine, in combination, a frame including a standard and an overhanging bracket-arm, a reciprocating needle carried by said bracket-arm, a complementary loop-taker, actuating mechanism interconnecting said needle and loop-taker and including a needle-actuating shaft carried by and extending longitudinally of the bracket-arm, and a driving motor carried by said frame and including a power-shaft extending transversely of said standard and needle-actuating shaft, and an operative connection between said shafts.
- 30 8. In a sewing machine, in combination, a frame including a hollow member, stitch-forming devices and operating mechanism therefor carried by said frame and including a shaft, a motor sustained by said frame and having a horizontally disposed power-shaft extending transversely of said first-mentioned shaft and at least partially within the hollow member of said frame, and an operative connection between said shafts.
- 35 9. In a sewing machine, in combination, a frame formed with an aperture, stitch-forming mechanism comprising a reciprocating needle and complementary loop-taking means incorporated in said frame, operating mechanism interconnecting said needle and loop-taking means, a motor-unit comprising a stator seated within said aperture and a rotor journaled in said stator and including a power-shaft projecting through said aperture and connected with said operating mechanism.
- 40 10. In a sewing machine, in combination, a frame formed with a hollow member, stitch-forming devices mounted in said frame, operating mechanism therefor including a rotary element housed within the hollow frame-member, and a motor detachably sustained as a unit by said frame and having a power-shaft operatively connected with said element of the operating mechanism within said hollow frame-member.
- 45 11. In a sewing machine, in combination, a frame formed with a hollow portion provided with spaced and aligned shaft bearings and with a lateral aperture intermediate the same, stitch-forming devices and operating mechanism therefor including a rotary shaft journaled in said bearings, a motor detachably sustained as a unit by said frame and having a power-shaft entering said aperture, and an operative connection between said shafts intermediate said bearings.
- 50 12. In a sewing machine, in combination, a frame having a standard, stitch-forming mechanism and operating means therefor sustained by the frame, said means including a shaft, and a motor unit detachably secured to the frame with its axis transverse to said shaft and standard, and a speed-reducing connection between said motor unit and said stitch-forming mechanism.
- 55 13. In a sewing machine, in combination, a frame having a work-support, overhanging arm and intermediate thin walled standard, said standard being provided with an opening surrounded by a seat, stitch-forming mechanism sustained by the frame, means for operating the stitch-forming mechanism including a shaft, a motor unit having a seat removably fitted to the seat on the standard with its axis transverse the standard and in non-intersecting relation with respect to said shaft, and a reduction gearing between the motor unit and the shaft.
- 60 14. In a sewing machine, in combination, a frame formed with an aperture, stitch-forming devices and operating mechanism therefor carried by said frame and including a rotary shaft carrying a spiral gear, and a motor sustained by said frame substantially in register with said aperture and having a power-shaft extending transversely of and in non-intersecting relation with said rotary shaft, said power-shaft carrying a spiral gear disposed in intermeshing relation with the spiral gear on said rotary shaft.
- 65 15. In a sewing machine, in combination, a frame, stitch-forming devices and operat-

ing mechanism therefor including a rotary shaft, a motor sustained by said frame and having a power-shaft disposed transversely of and in non-intersecting relation with said 5 rotary shaft, and an operative connection between said shafts comprising a worm fixed to said power-shaft and a gear meshing with said worm and mounted on said rotary shaft to transmit rotary movement 10 from the power-shaft to the said rotary shaft at a reduced speed.

16. In combination, a sewing machine frame having a hollow portion formed with a lateral aperture, stitch-forming devices 15 and operating mechanism therefor including a rotary element extending within the hollow frame member, and an electric motor comprising a cup-shaped frame having its body fitted within said aperture to afford 20 a closure therefor within said hollow frame portion and provided with an inwardly extending bearing boss, and a power-shaft journaled in said bearing boss and operatively connected adjacent the same with 25 said rotary element and sustaining upon its outer end portion an armature disposed within the cavity afforded by the cup-shaped motor frame.

17. In a sewing machine, in combination, 30 a frame formed with a hollow member having a lateral aperture, stitch-forming devices and operating mechanism therefor including a rotary element within the hollow frame member, a motor detachably sustained by said frame and extending through said aperture and partially housed within the frame, said motor comprising a power-shaft operatively connected with said rotary element, and a hollow cover of less depth 35 than that of said motor for housing that portion of the latter disposed outside of said frame.

18. In a sewing machine, in combination, 40 a frame formed with a hollow member having a lateral aperture, stitch-forming devices and operating mechanism therefor including a rotary element within the hollow frame member, a motor disposed partially exterior to and detachably sustained by said 45 frame in register with said aperture with its shaft operatively connected with said rotary element, and a cover applied to said aperture for housing that portion of the motor outside of said frame.

55 19. In a sewing machine, in combination, 50 a frame formed with a hollow portion, stitch-forming devices and operating mechanism therefor including a rotary element housed within the hollow frame portion, a 55 motor-unit comprising a stator detachably sustained by said frame and a rotor having a power-shaft journaled in said stator and operatively connected with said element of the operating mechanism within said hollow 60 frame portion, and a positively acting cou-

pling device whereby the motor may be caused to actuate the stitch-forming devices or to operate independently thereof.

20. In a sewing machine, in combination, 70 stitch-forming mechanism including a reciprocating needle, a loop-taker and interconnecting mechanism for actuating said needle and loop-taker in timed relation, a driving motor mounted on the machine and detachable independently of said interconnecting mechanism, automatically disconnectible means for connecting the stitch-forming mechanism and motor, and means for manually disconnecting the stitch-forming mechanism from the motor. 75

80 21. In a sewing machine, a plurality of main-shaft sections, stitch-forming means actuated by one of said shaft-sections, a plurality of actuating means each adapted for independent connection with or disconnection from another of said shaft-sections, and means for connecting and disconnecting said sections at will. 85

90 22. In a sewing machine, in combination, stitch-forming mechanism, operating means therefor including a rotary shaft formed in separate driving and driven sections, an operative connection between the driven shaft section and the stitch-forming mechanism, manual driving means connected with the 95 driving shaft section, a motor unit also connected with said driving shaft section, and means for coupling and uncoupling said shaft sections.

95 23. In a sewing machine, in combination, 100 stitch-forming mechanism, an actuating shaft therefor, a plurality of driving devices including a motor and a belt pulley, and means for transmitting power to said actuating shaft from either of said driving 105 devices including a driving element common to both.

110 24. In a sewing machine, in combination, stitch-forming mechanism, an actuating shaft therefor, a second shaft adapted to be 110 operatively connected with and disconnected from said actuating shaft, and a plurality of differentially movable driving devices adapted to drive said actuating shaft through the medium of said second shaft. 115

115 25. In a sewing machine, in combination, 120 stitch-forming mechanism, a sectional main-shaft, a plurality of differentially movable main-shaft driving devices, and means for operatively controlling the connection between said shaft-sections for effecting and discontinuing the transmission of power to meet the requirements of operating conditions.

125 26. In a sewing machine, in combination, 125 a frame, stitch-forming devices, operating means therefor including a rotary shaft formed in end-to-end driving and driven sections of which the latter is operatively connected with the stitch-forming devices, 130

- a motor operatively connected with the driving shaft-section, additional manually actuated driving means also applied to said driving shaft-section, and a coupling device 5 for operatively connecting and disconnecting said shaft-sections and provided with controlling means operable from the end of the driving shaft-section opposite said coupling means.
- 10 27. In a sewing machine, in combination, a frame, stitch-forming devices, operating means therefor including a rotary shaft formed in end-to-end driving and driven sections of which the latter is operatively connected with the stitch-forming devices, a motor operatively connected with the driving shaft-section, additional manually actuated driving means also applied to said driving shaft-section, and a coupling device 15 for operatively connecting and disconnecting said shaft-sections.
- 20 28. In a sewing machine, in combination, a frame, stitch-forming devices, operating means therefor including a rotary shaft formed in end-to-end driving and driven sections of which the latter is operatively connected with the stitch-forming devices, a balance-wheel sustained by and connected to rotate with the driven shaft-section, a 25 motor sustained by said frame, an operative connection between said motor and the driving shaft-section including a one-way-acting clutch for permitting such shaft-section to be turned forwardly independently of the motor, and a coupling device for operatively 30 connecting and disconnecting said shaft-sections.
- 35 29. In a sewing machine, in combination, a frame, stitch-forming devices, operating means therefor including a rotary shaft 40 formed in end-to-end driving and driven sections of which the latter is operatively connected with the stitch-forming devices, a balance-wheel applied to the driving shaft-sections, a hand-operated driving device with means for connecting it to and disconnecting it from said driving shaft-section, a motor sustained by said frame, an operative connection between said motor 45 and the driving shaft-section including a one-way-acting clutch for permitting such shaft-section to be turned forwardly independently of the motor, and a coupling device for operatively connecting and disconnecting said shaft-sections.
- 50 30. In a sewing machine, in combination, a frame, stitch-forming devices and operating mechanism therefor mounted within said frame, a driving wheel connected with said mechanism and disposed exterior to said frame, a motor detachably sustained as a unit by said frame and having a power-shaft disposed partially exterior to said frame and extending into the latter, and a 55 driving connection between said power- shaft and said operating mechanism intermediate said stitch-forming devices and the driving wheel.
31. In a sewing machine, in combination, a frame, a reciprocating needle and complementary loop-taking means incorporated in said frame, interconnecting mechanism for actuating the needle and loop-taking means in properly timed relation to one another, a rotary element distinct from said interconnecting mechanism and journaled in said frame, a belt-wheel carried by said element, an electric motor for driving said element, and means for establishing and interrupting driving relation between said element and 70 said interconnecting mechanism, whereby said belt-wheel may be driven independently of said interconnecting mechanism.
32. In a sewing machine, in combination, a frame, a reciprocating needle and complementary loop-taking means incorporated in said frame, interconnecting mechanism for actuating the needle and loop-taking means in properly timed relation to one another, a belt-wheel mounted for rotation independently of said interconnecting mechanism, an electric motor for driving said belt-wheel, means for establishing and interrupting driving relation between said belt-wheel and 75 said interconnecting mechanism, and a one-way acting clutch between said motor and belt-wheel.
33. In a sewing machine, in combination, stitch-forming mechanism, a supporting framework, an actuating shaft, a plurality of differentially movable driving devices supported by said framework, and a disconnectible connection common to said driving devices and disposed between said driving devices and said actuating shaft.
34. In a sewing machine, in combination, stitch-forming mechanism including a reciprocating needle and a loop-taker, operating mechanism interconnecting said needle and loop-taker, manual driving means connected 100 with said operating mechanism, a detachable motor unit disposed between said operating mechanism and said manual driving means, and a one-way driving connection between said motor unit and said operating 105 mechanism, whereby the stitch-forming mechanism may be actuated by said motor or independently thereof by said manual driving means.
35. In a sewing machine, a frame, stitch-forming mechanism carried by said frame, electro-magnetic means detachably mounted in said frame for driving said stitch-forming mechanism, means for manually driving said stitch-forming mechanism, means for disconnecting either of said driving means from said stitch-forming mechanism, and separate means for disconnecting both of 110 said driving means from said stitch-forming mechanism.
36. In a sewing machine, a frame, stitch-forming mechanism carried by said frame, electro-magnetic means detachably mounted in said frame for driving said stitch-forming mechanism, means for manually driving said stitch-forming mechanism, means for disconnecting either of said driving means from said stitch-forming mechanism, and separate means for disconnecting both of 115 said driving means from said stitch-forming mechanism.
37. In a sewing machine, a frame, stitch-forming mechanism carried by said frame, electro-magnetic means detachably mounted in said frame for driving said stitch-forming mechanism, means for manually driving said stitch-forming mechanism, means for disconnecting either of said driving means from said stitch-forming mechanism, and separate means for disconnecting both of 120 said driving means from said stitch-forming mechanism.
38. In a sewing machine, a frame, stitch-forming mechanism carried by said frame, electro-magnetic means detachably mounted in said frame for driving said stitch-forming mechanism, means for manually driving said stitch-forming mechanism, means for disconnecting either of said driving means from said stitch-forming mechanism, and separate means for disconnecting both of 125 said driving means from said stitch-forming mechanism.
39. In a sewing machine, a frame, stitch-forming mechanism carried by said frame, electro-magnetic means detachably mounted in said frame for driving said stitch-forming mechanism, means for manually driving said stitch-forming mechanism, means for disconnecting either of said driving means from said stitch-forming mechanism, and separate means for disconnecting both of 130 said driving means from said stitch-forming mechanism.

36. In a sewing machine, a frame having an opening, stitch-forming mechanism carried by said frame, manual means for actuating said stitch-forming mechanism, a readily detachable motor constructed separately from said frame and adapted to enter said opening, and coöperating driving connections carried by said motor and manual actuating means which are brought into operative relation upon insertion of said motor in said opening.
37. In a sewing machine, stitch-forming mechanism, a shaft, means for connecting said shaft to the stitch-forming mechanism at will, motor means for driving said shaft, means for manually driving said shaft, and means for automatically releasing said motor drive means when the shaft is manually driven.
38. In a sewing machine, stitch-forming mechanism, a plurality of actuating means therefor, a plurality of means for individually releasing said actuating means from said stitch-forming mechanism, and common means for releasing all of said actuating means from said stitch-forming mechanism.
39. In a sewing machine, in combination, a main-shaft, a plurality of driving devices comprising a motor drive, a belt-drive and hand drive independent of each other, and means for actuating said shaft from any one of said devices.
40. In a sewing machine, in combination, stitch-forming mechanism, a rotary shaft, belt-driven actuating means for said shaft, hand-operated actuating means detachably connected with said shaft, and a detachable motor-unit also connected with said shaft independently of the belt-driven and hand-operated actuating means.
41. In a sewing machine, in combination, stitch-forming mechanism, a rotary shaft, belt-driven actuating means for said shaft, hand-operated actuating means detachably connected with said shaft, a motor unit, and a clutch connection between said motor unit and the stitch-forming mechanism whereby the motor may remain at rest during the use of the belt-driven or hand-operated actuating means.
42. In a sewing machine, in combination, a frame, stitch-forming devices carried thereby, operating means connecting said devices, a belt-wheel connected to said operating means, a hand-operated driving device with means for connecting it to and disconnecting it from said operating means, a motor-unit sustained by said frame, and an operative connection between said motor-unit and said operating means.
43. In a sewing machine, in combination, a frame, stitch-forming devices carried thereby, operating means connecting said devices, a belt-wheel connected to said operating means, a hand-operated driving device
- 5 10 15 20 25 30 35 40 45 50 55 60 65 70 75 80 85 90 95 100 105 110 115 120 125 130
- with means for connecting it to and disconnecting it from said operating means, a motor-unit sustained by said frame, and an operative connection between said motor-unit and said operating means, said last-mentioned connection including a one-way acting clutch for permitting said operating means to be turned forwardly independently of the motor.
44. In a sewing machine, in combination, a frame including a standard and an overhanging bracket-arm, stitch-forming devices carried by said frame, operating means connecting said devices, a belt-wheel mounted at the side of said standard opposite the bracket-arm and connected to said operating means, a hand-operated driving device disposed below said belt-wheel with means for connecting it with and disconnecting it from said operating means, a motor sustained by said frame at the rear of said standard, and an operative connection between said motor and said operating means.
45. In combination, a sewing machine frame, stitch-forming devices and operating means therefor including a rotary shaft extending lengthwise of said frame, and a motor mounted upon the machine frame and comprising a frame constructed with aligned shaft bearings extending crosswise of the machine frame and having an intermediate open-topped gear cavity and an oil pocket extending from the same lengthwise of one of said shaft bearings to catch lubricant overflowing from said cavity when the machine frame is canted laterally, and a power-shaft journaled in said bearings and carrying a gear entering said cavity and operatively connected with said rotary shaft.
46. In combination, a sewing machine frame, stitch-forming devices and operating means therefor including a rotary shaft extending lengthwise of said frame, and a motor mounted upon the machine frame and comprising a frame constructed with aligned shaft bearings extending crosswise of the machine frame and having an intermediate open-topped gear-cavity and oil-pockets extending oppositely from the same and lengthwise of said shaft bearings to catch lubricant overflowing from said cavity when the machine frame is canted laterally in either direction, and a power-shaft journaled in said bearings and carrying a gear entering said cavity and operatively connected with said rotary shaft.
47. In combination, a sewing machine frame, stitch-forming devices and operating means therefor including a rotary shaft extending lengthwise of said frame, and a motor mounted upon the machine frame and comprising a frame constructed with aligned shaft bearings extending crosswise of the machine frame and having an intermediate open-topped gear-cavity, a U-shaped rib be-

ing formed upon the top of one of said bearings to afford a lubricant-overflow receptacle at one side of said cavity, and pockets being formed in the wall of and at the opposite 5 side of said receptacle to receive overflow lubricant at the corresponding side of said cavity, and a power-shaft journaled in said bearings and carrying a gear entering said cavity and operatively connected with said 10 rotary shaft.

48. A sewing machine comprising a frame, a reciprocating needle, a complementary loop-taker, and interconnecting mechanism for driving said needle and loop-taker in properly timed relation, all carried by said frame, 15 a driving shaft additional to said intercon-

necting mechanism and journaled in said frame, a belt-driven balance-wheel carried by said driving shaft, and means for establishing and interrupting driving relation 20 between said driving shaft and said interconnecting mechanism, said frame being formed with a seat adapted for reception of a motor-unit in driving relation with said shaft when it is desired to operate the machine by power applied independently of the balance-wheel.

In testimony whereof we have signed our names to this specification.

OLIVER L. DOSCH.
MARTIN HEMLEB.
